UNITED STATES PATENT OFFICE

ROY W. JOHNSON, OF COLUMBUS, OHIO, ASSIGNOR TO THE CHECKER CAB MANUFACTURING COMPANY, OF KALAMAZOO, MICHIGAN, A CORPORATION OF NEW JERSEY

DESIGN FOR A COMBINED TAIL AND STOP LIGHT FOR MOTOR VEHICLES

Application filed September 12, 1930. Serial No. 36,952. Term of patent 3½ years.

To all whom it may concern:

Be it known that I, ROY W. JOHNSON, a citizen of the United States, residing at Columbus, in the county of Franklin and State of Ohio, have invented a new, original, and ornamental Design for Combined Tail and Stop Light for Motor Vehicles, of which the following is a specification, reference being had to the accompanying drawing, forming part thereof.

Figure 1 is a front elevation of the combined tail and stop light for motor vehicles showing my new design and

Figure 2 is a side elevation thereof.

I claim:

The ornamental design for a combined tail and stop light for motor vehicles, as shown.

ROY W. JOHNSON.
